CUP DISPOSAL SYSTEM

Samuel D. Polsen and Sven Herbert Nelson,
Bridgeport, Conn., assignors of one-fourth to
Blanche H. Polsen and one-fourth to Mildred
P. Nelson, both of Bridgeport, Conn.

Application August 19, 1941, Serial No. 407,511

10 Claims. (Cl. 100—4)

This invention relates to new and useful improvements in dispensing apparatus and has particular relation to the disposal of used receptacles or cups of paper or similar destructible material ordinarily supplied to the patrons of devices or machines dispensing liquids such as hot or cold drinks, soups, and the like.

To a large extent receptacles or cups of paper or other destructible material are supplied by liquid dispensing devices for use by patrons of such devices and the disposal of such cups, after their use, presents a problem of sanitation and also of the handling of considerable bulk.

The present invention provides for the disposal of such used cups or receptacles in such a manner that there is no litter about the dispensing machine, in such a manner that there is no spilled liquid at the outside of the machine, in such a manner that the used cups or receptacles are reduced to a small bulk and packaged for convenient removal from the vicinity of the dispensing machine, and in such a manner that all surfaces engaged by the used or discarded cups or receptacles or by any liquid left in them are readily renewable each time the discarded cups or receptacles are taken from the dispensing machine.

Since the used cups or other receptacles are reduced in bulk and packaged or collected in a removable container of destructible material, and since the surfaces of the parts likely to be contaminated are renewable as above set forth it will be understood that the device of the invention provides for collection into a relatively small removable container of a large number of discarded cups or other receptacles and that this in connection with the other features mentioned provides for a convenient and easy maintenance of sanitary conditions about the dispensing device with which the means of the invention is used.

Other objects and advantages of the invention will be apparent from a consideration of the following detailed description taken in connection with the accompanying drawing wherein satisfactory embodiments of the invention are shown. However, it is to be understood that the invention is not limited to the details disclosed but includes all such variations and modifications as fall within the spirit of the invention and the scope of the appended claims.

In the drawing:

Fig. 1 is a view partly in side elevation and partly in section showing the apparatus of the invention as located in a compartment of the

cabinet of a liquid dispensing device, a side wall of the cabinet being removed.

Fig. 2 is a sectional view taken as along the plane of the line 2—2 of Fig. 1;

Fig. 3 is a detail sectional view taken as along the line 3—3 of Fig. 1; and

Fig. 4 is a view somewhat similar to Fig. 1 but showing a slight modification.

Referring in detail to the drawing and at first 10 more particularly to Figs. 1, 2 and 3, at 10 is generally indicated a portion of the cabinet of a dispensing apparatus which may be coin controlled or otherwise. The machine includes means (not shown) for supplying to a patron a cup or other 15 receptacle, generally of paper or other destructible material, adapted after use to be discarded and also for supplying to the patron a drink or the like which may be in the cup or receptacle when the latter is delivered or which the patron 20 catches in such cup or other receptacle. The means of the invention may be mounted in a compartment of the cabinet of a machine such as described and is herein so disclosed although it 25 is to be understood that it may be mounted in any separate housing if such is desired.

A partition 11 serves to form a compartment 12 at one side of the cabinet 10 and the means of the invention is particularly concerned with this compartment 12 and is for the most part mounted 30 therein. At the side of partition 11 opposite that at which the compartment 12 is located there is the space or compartment 13 for the reception and mounting of any suitable apparatus (not shown) for the dispensing of cups or other 35 receptacles and the food or drink.

In the front wall 14 of the compartment 12 is a doorway 15 normally closed by a small door 16 shown as pivotally mounted. Within the compartment in position to receive used cups inserted 40 through the doorway 15 is a platform 17 inclining away from the doorway. As clearly shown in Fig. 3 the platform is somewhat channel shaped in transverse section including a bottom wall 18 and side flanges or walls 19. Platform 17 is supported from the partition 11 or otherwise by any 45 suitable or desired means (not shown).

At the inner lower end of the platform 17 in position to receive any material or article moving off such end is a container 20 preferably comprising a bag of paper or other destructible material and also preferably of a material which has been treated to render it substantially liquid proof. Container 20 is removably secured in place by means of spring clips 21 and 22 on the 50 rear wall 23 of the compartment and the under

side of the platform 17 respectively. Thus the container is secured in place and its mouth held open or expanded to receive any article or material falling from the lower end of the platform 17.

It will be clear that the container 20 may be readily removed from the compartment 12 through a doorway normally closed by a door 24 hinged to the cabinet at 25. When the door 24 is open it is merely necessary to slip the upper edges of the container from under the clips 21 and 22 in order to lift the container from compartment 12. Thereafter a new container is placed in the compartment and the edges of its open end are clamped by the clips 21 and 22 securing it in place to receive any material or article moving off the lower end of platform 17.

Spaced above the inner lower end of platform 17 is a stop 26 so located that a cup or receptacle 37, when in normal open condition, can not pass under the stop and is prevented from falling off the platform thereby. According to the invention while a cup or other receptacle is being held by the stop 26 it is crushed to reduce its bulk whereby a large number of the cups after use may be held in the container 20 without the latter being of extremely large capacity.

For the described purpose a rocker arm 27 is pivotally mounted intermediate its ends as on a short shaft or pin 28 extending from the partition 11 into the compartment 12. To the rear end portion of arm 27 a pivot pin 29 attaches the upper end of a rigid link or member 30 the lower end portion of which is disposed immediately forwardly of the stop 26 and carries a crusher foot 31 extending forwardly over the inner lower portion of platform 17. A pin 32 pivotally connects the upper end of a link 33 to the forward end of the arm 27 and on the lower end of such link is a ball-like portion 34 received in a cup or channel member 35 rigid with the door 16. Link 33 carries a counter weight 36 the purpose of which will be fully set forth.

The construction thus far described may be used for our purpose. In use a patron having obtained a drink or the like from the dispensing machine discards his used cup or other receptacle by pushing it through the doorway 15 and it passes onto the platform 17 and slides or rolls down the same until it engages stop 26 as in the case of the cup 37 shown in the drawing. The weight 36 on the link 33 maintains the door 16 closed and the arm 27 and parts attached thereto in the positions in which they are shown by the full lines in Fig. 1, this being the normal positions of the parts.

Now when the next user pushes a cup or receptacle through doorway 15 the cup 37 will be crushed. Thus cup 38 (Fig. 1) is being pushed through the doorway and as door 16 is pushed open and swings on its pivotal mounting the link 33 is forced upwardly and rocks the arm 27 to the dotted line position of Fig. 1. As this movement takes place the link 30 is forced downwardly and the crusher foot 31 engages the cup 37 crushing the same to a flat condition whereby its bulk is substantially reduced. When the cup or receptacle 38 is inside it slides or rolls to a position against the stop 26. Weight 36 acts to close the door 16, rock the arm 27 back to normal position and raise the link 30 and the crusher foot 31 so that the latter is elevated and out of the way when the cup or receptacle slides or rolls down platform 17 to a position against the stop 26.

During the time that the parts are returning

to their normal positions and after the cup 37 has been crushed the latter passes under the stop 26 and falls to the container 20. At the end of a cycle of operation the second cup or receptacle is therefore against the stop 26, the first cup or receptacle has been crushed flat and is in the container 20, and the door 16 is closed to exclude flies or other insects. Since the cups or receptacles are crushed flat before entering the container 20 it will be understood that without the latter being unduly large it will be capable of receiving a very large number of cups or other receptacles. Therefore used cups or the like will not be spilled about the machine for lack of space into which the users of the machine may place the cups or receptacles after using them.

As a further step toward sanitation a roll of paper or other destructible material 39, preferably treated to render it substantially liquid proof, is mounted in compartment 12 preferably below the platform 17, as on a pin 40. A portion of the paper 39 is lead over the top side of the platform 17 as at 41 and then the free end of the paper is carried to the under side of the platform and secured under the clip 22 previously described.

With this construction the drops of material usually remaining in a cup when it is discarded are kept from contact with the platform proper 30 and drain into the container 20 off the paper 41. When the maintenance man removes the container 20 and replaces it with a clean one he releases the end of the paper from the clip 22 and draws a clean piece of paper over the platform 17 and tears off the used paper placing it in the container he is removing and clamps the new free end of the paper under the clip 22.

In a manner similar to the above a roll of paper 42 is mounted on a pin 43 above the crusher foot 40 31. Paper 42 is preferably treated to render it substantially liquid proof and a portion 44 of it is carried downwardly about the crusher foot as by being passed under a guide member 45. The free end of the paper is secured in place as by 45 being clamped under a spring clip 46 on the rear side of the link 30. At the same time that the paper over the platform 17 is renewed the used portion of paper 42 is torn off and a clean portion thereof drawn under the guide 45 and about 50 the foot 31 and secured by the clip 46.

From the above it will be understood that through the use of the means of the invention the machine may be kept in a clean and sanitary condition and that a small container 20 55 may be used to hold a very large number of discarded cups or other receptacles. Each time the maintenance man renews the supply of dispensable material in the machine he removes the container 20 and its contents and replaces it with 60 a clean fresh container. At the same time he easily and quickly renews the surfaces of the platform 17 and the crusher foot 31 carrying away in the container the soiled portions of the paper from the rolls 39 and 42.

In the modification of Fig. 4 where the parts are the same they have been given the same reference characters. In the device of such figure the crusher is designed to be power operated as by power from some moving part of a dispensing apparatus in the compartment 13 of the cabinet 10. Thus the upper end of the link 30 is connected by a pivot 50 with the outer end of a crank arm 51 mounted on a shaft 52 driven by a motor 53. An arm 54 mounted on the pivot 75 28 has a slot 55 through which the pivot pin 50

passes and by which its movement is guided. With this construction, with each cycle of the machine's operation or with each revolution of the shaft 52, the link 30 carrying the crusher foot is given a reciprocating movement carrying such foot downward for a crushing operation and then returning it to its normal position.

Having thus set forth the nature of our invention, what we claim is:

1. In an apparatus for disposing of used receptacles of paper and the like, a cabinet having a doorway, a stationary platform in said cabinet in position to receive receptacles inserted through said doorway, said platform having an inclined upper surface with its higher portion adjacent said doorway, said platform having a free lower end, a stop above the lower end of said platform in position to prevent the receptacles in normal condition moving off the lower end of the platform, and means operating immediately forwardly of said stop to crush the receptacles and reduce their bulk after which they may move under the stop and off the lower end of the platform.

2. In an apparatus for disposing of used receptacles of paper and the like, a cabinet having a doorway, a platform in said cabinet in position to receive receptacles inserted through said doorway, a stop above said platform in position to prevent receptacles in normal condition moving from the platform, a normally elevated crusher operating immediately forwardly of the stop and adapted on being moved downwardly toward the platform to crush a receptacle against the platform and reduce its bulk after which it may pass under the stop and off the platform, a door normally closing said doorway, and means operated by said door as the latter is opened to give said crusher its downward stroke.

3. In an apparatus for disposing of used receptacles of paper and the like, a cabinet having a doorway, a platform in said cabinet in position to receive receptacles inserted through said doorway, a stop above said platform in position to prevent receptacles in normal condition moving from the platform, a rocker arm pivoted intermediate its ends and disposed above said platform, a rigid link pivoted to one end of said rocker arm, a crusher foot on the lower end of said link and located immediately forwardly of said stop, a link pivoted to the other end of said rocker arm, a door normally closing said doorway, and a connection between the lower end of said other link and the said door whereby as said door is opened said rocker arm is rocked on its pivot and said crusher foot is forced downwardly toward the platform to crush any receptacle thereon at the forward side of said stop to reduce the bulk of such receptacle and permit its movement under the stop and off the platform.

4. In an apparatus for disposing of used receptacles of paper and the like, a cabinet having a doorway, a platform in said cabinet in position to receive receptacles inserted through said doorway, a stop above said platform in position to prevent receptacles in normal condition moving from the platform, a rocker arm pivoted intermediate its ends and disposed above said platform, a rigid link pivoted to one end of said rocker arm, a crusher foot on the lower end of said link and located immediately forwardly of said stop, a link pivoted to the other end of said rocker arm, a door normally closing said doorway, a connection between the lower end of said other link and the said door whereby as the door is opened said rocker arm is rocked on its pivot and said crusher

foot is forced downwardly toward the platform to crush any receptacle thereon at the forward side of said stop to reduce the bulk of such receptacle and permit its movement under the stop and off the platform, and said second mentioned link weighted whereby to return said door to closed position and said rocker arm and crusher to normal positions on release of said door.

5. In an apparatus for disposing of used receptacles of paper and the like, a cabinet having a doorway, a stationary platform in said cabinet in position to receive receptacles inserted through said doorway, said platform arranged with its upper surface declining from said doorway, said platform having a free lower end, a stop above the lower end of said platform in position to prevent receptacles in normal condition moving from the lower end of the platform, an arm pivoted in said cabinet above said platform, a rigid link connected at its upper end with said arm, a crusher foot on the lower end of said link and located immediately forwardly of said stop, and means to rock said arm on its pivot to force said crusher foot toward the platform to crush any paper receptacle thereon to reduce the bulk of such receptacle so that it may pass under the stop and off the lower end of the platform.

6. In an apparatus for disposing of used receptacles of paper and the like, a cabinet having a doorway, a platform in said cabinet in position to receive receptacles inserted through said doorway, a stop above said platform in position to prevent the receptacles in normal condition moving from the platform, an arm pivoted in said cabinet above said platform, a rigid link connected at its upper end with said arm, a crusher foot on the lower end of said link and located immediately forwardly of said stop, a door normally closing said doorway, and means operated by said door as the latter is opened to rock said arm on its pivot and force said crusher foot downwardly toward the platform and crush any receptacle thereon to reduce its bulk so that it may pass under the stop and off the platform.

7. In an apparatus for disposing of used receptacles of paper and the like, a cabinet having a doorway, a stationary platform in said cabinet in position to receive receptacles inserted through said doorway and declining from the latter and free at its lower end, a stop above the lower end of said platform in position to prevent the receptacles in normal condition moving off the lower end of the platform, means operating immediately forwardly of said stop to crush the receptacles held by said stop and reduce their bulk after which they may pass under the stop, and said platform comprising a bottom wall and side walls.

8. In an apparatus for disposing of used receptacles of paper and the like, a cabinet having a doorway, a stationary platform in said cabinet in position to receive receptacles inserted through said doorway, said platform arranged with its upper surface declining from said doorway, a stop above the lower end of said platform in position to prevent the receptacles in normal condition moving from the lower end of the platform, an arm pivoted in said cabinet above said platform, a rigid link connected at its upper end with said arm, a crusher foot on the lower end of said link and located immediately forwardly of said stop, a door normally closing said doorway, means operated by said door as the latter is opened to rock said arm on its pivot and force said crusher foot downwardly toward the

platform and crush any receptacle thereon to reduce its bulk so that it may pass under the stop and off the platform, and means for closing said door and returning said arm, link and crusher foot to their normal positions on release of said door after the opening thereof.

9. In an apparatus for disposing of used receptacles of paper and the like, a cabinet having a doorway, a platform in said cabinet in position to receive receptacles inserted through said doorway, a stop above said platform in position to prevent receptacles in normal condition moving from the platform, an arm in said cabinet and pivotally mounted above said platform, a rigid link connected at its upper end with said arm, a crusher foot on the lower end of said link and located immediately forwardly of said stop, and power means operable to rock said arm on its pivot and force said crusher foot toward the

platform to crush any receptacle thereon to reduce its bulk so that it may pass under the stop and off the platform.

10. In an apparatus for disposing of used receptacles of paper and the like, a cabinet having an opening, a rigid stationary platform in said cabinet in position to receive receptacles inserted through said opening, said platform having its upper surface declining from said opening, said platform free at its lower end, a stop limiting movement of an uncrushed receptacle along said platform and definitely positioning the same thereon, and means working immediately ahead of said stop for crushing against said platform a receptacle positioned by said stop to reduce the bulk of the receptacle for movement past said stop and off the platform.
